COMBINED PUNCHING AND RIVETING MACHINE

William E. Marchant, Detroit, Mich., assignor to
Engineering and Research Corporation, Wash-
ington, D. C., a corporation of the District of
Columbia

Application June 21, 1934, Serial No. 731,685

5 Claims. (Cl. 78—49)

This invention relates to a combined punching and riveting machine.

A combined punching and riveting machine is shown in the prior application of Lee L. Marchant, Serial No. 523,956, filed March 20, 1931.

This invention relates to a modification of the combined punching and riveting machine shown in the above-mentioned application, and more particularly contemplates a novel floating pilot for maintaining the punched work in proper position upon the anvil with the rivet holes aligned and held against slippage to prevent offset of one rivet hole relative to the other.

In the drawings:

Fig. 1 is a fragmentary elevation showing the combined punching and riveting machine; in the full lines the machine is shown with the parts positioned before punching and in the dotted lines the position of the parts during the punching operation.

Fig. 2 is a detail perspective of the head showing the work being punched.

Fig. 3 is a detail sectional view showing the relative position of the parts after the work has been punched with the pilot engaging the work in the punched holes and the punch retreating.

Fig. 4 is a detail view showing the head oscillated with the punching head removed from over the anvil and with the rivet head positioned over the anvil.

Fig. 5 is a detail showing the head portion of the machine after the work has been punched and ready for riveting.

Fig. 6 shows the position of the parts just after upsetting the rivet.

Referring more particularly to the drawings there is shown a frame 1 on which is rotatably mounted the driving wheel 2 which is operatively connected to a motor (not shown) by the belt 3. The upper portion of the frame 1 takes the form of a throated yoke having an upper jaw 4 and a lower jaw 5. The upper jaw 4 has journaled therein, as at 6, the combined punching and riveting heads 7 and 8 respectively. The punching head 7 carries the reciprocable punch 9 and is driven by the driving pin 10 and retracted by the coil spring 11 mounted within the head 7.

The rivet head 8 has reciprocably mounted therein the rivet set 12 which is also driven by the driving pin 10. The lower end of the rivet head is provided with a suitable rivet shoe 13.

The rivets 14 may be fed to the shoe 13 by any suitable rivet guide 15 from the rivet hopper 16.

The rivet shoe 13 may be of any of the well-known expandable types which are expanded by

the rivet set during the riveting operation to feed the rivet to the work.

The driving pin 10 may be operatively connected to the driving wheel 2 in any well-known and suitable manner such as indicated generally at 5 17, and including a clutch 18. The clutch 18 is arranged to be controlled through the foot pedal 19 which is operatively connected with the clutch through the linkage generally designated 20. As shown in Fig. 1 the pedal 19 and linkage 20, in 10 the full lines indicate the clutch disengaged and in the dotted lines engaged.

The rotatable punching and riveting head, as shown in Fig. 4, is provided with a crank arm 21 and a link 22 which connects the crank arm 21 15 to the bell crank lever 23, Figs. 1 and 5. The bell crank 23 is connected to the main foot pedal lever 24, which is pivoted as at 25, through the link 26, bell crank 27 pivoted at 28, and the link 29. Hence, when the main foot pedal lever 24 is 20 swung from the position shown in Fig. 1 to that shown in Fig. 5, the punching head 7 is swung from a position over the anvil 30 and the riveting head 8 is swung from the position shown in Fig. 2 to that shown in Fig. 4, over the anvil 30. The 25 rivet shoe 13 is slidably mounted in the riveting head 8 and yieldably retained in retracted position by a coil spring (not shown) in a similar fashion to that used with the punch 9.

The punching head has slidably mounted 30 thereon a clamping die 60 having a projecting lug 31 which is arranged to be engaged by the lever 32. The lever 32 is pivotally mounted, as at 33, and connected to a link and foot pedal similar to link 26 and foot pedal 24 and mounted by 35 the side of link 26 and pedal 24.

The lower jaw 5 of the frame carries the anvil 30 which is provided with a slot 34 in which is mounted a flat spring 35. The slot 34 and spring 35 provide for the ejection of the slug during 40 the punching operation. The anvil 30 has slidably mounted therein the pilot 36, the piloting end 37 of which corresponds in size with the punch 9. The head 5 has reciprocably mounted therein the cam member 38 provided with the 45 cam surface 39 and the pilot seat 40. The member 38 is operatively connected to the bell crank lever 41 which in turn is operatively connected to the link 26 as at 42. The anvil may be provided with a suitable stripper 47 yieldably supported by 50 the coil spring 48.

The operation of the machine is as follows: The work 50 is inserted over the anvil 30 and beneath the punch 9. By operation of lever 32 through a foot pedal, as above described, the work 55

is clamped between the clamping die 60 and anvil 30. The rotary punching and riveting heads normally are positioned with the punch over the anvil. The operator now manipulates 5 the pedal 19 to engage the clutch 18 which causes the driving pin to project the punch 9 through the work 50, as shown in Fig. 2. At this time the pilot 36 is in retracted position, as shown in Figs. 1 and 2, so that the head 37 is retracted sufficiently 10 within the mouth of the anvil 30 to permit operation of the punch. The punching slug is ejected from the anvil 30 through the slot 34 by the flat spring member 35.

The punch 9 is withdrawn from the work by 15 the spring 11 as soon as the punching operation is completed. The pedal lever 24 and associated linkage is shifted to the position shown in Fig. 5, thus swinging the punching head 7 from its position over the anvil and bringing the riveting head 8 over the anvil.

As the foot pedal lever 24 swings to shift the combined punching and riveting head the cam member 38 is slid from the position shown in Fig. 1 through that shown in Fig. 3 to the position shown in Fig. 6. During this movement of 25 the cam member 38, the cam 39 projects the pilot 36 upwardly through the punched opening in the work 50 where it maintains the work properly aligned on the anvil. With the work on the 30 anvil and the pilot 37 in position through the hole in the work, the pedal 19 is now operated to engage the clutch 18. At this time the driving pin 10 projects the rivet set 12 which carries the loaded rivet shoe down to the punched work 35 and finally spreads the rivet shoe 13 to release the rivet. The lower end of the rivet 14 engages the pilot 37 which pilots the rivet through the punched hole in the work. At this time the cam 38 is in the position shown in Fig. 6, whereupon the pilot 36 retreats to the seat 40 upon the member 38.

The pilot 36 is of the proper length so that when seated upon the seat 40 the top face of the portion 37 becomes a part of the anvil 30 and thus 45 assists in upsetting the rivet 14 as the rivet set 12 moves further down, as shown in Fig. 6. As soon as the rivet is upset and the clutch disengaged, the combined punching and riveting head shifts so that the punch is again over the 50 anvil thus bringing the cam member 38 back to its original position shown in Fig. 1.

I claim:

1. A combined punching and riveting machine comprising a frame, an anvil supported by said 55 frame, a pilot floated in said anvil, a combined punching and riveting head shiftably mounted on said frame, a punch and a rivet set carried by said head whereby the said head may be shifted to alternately position the punch and the rivet set over said anvil, means operatively connected and coordinated with the shiftable head for projecting the pilot through said work after the punching operation to hold the work in position and for holding the pilot with the end of the pilot 60 flush with the face of the anvil during the upsetting of a rivet whereby the rivet engages the pilot and is guided by the pilot through the work prior to being upset, and a second means for removing the first mentioned means from beneath the pilot whereby the pilot retreats within the anvil during the punching operation.

2. A punching and riveting machine comprising an anvil having an opening therein, a pilot movably mounted in the opening in the said 70 anvil and projectable to a position where a por-

tion of the pilot extends beyond the mouth of the opening and retractable to another position where the end of the pilot is substantially flush with the mouth of the opening to serve as part of the anvil, a shiftable head shiftable to alternately position the punch and rivet set over said anvil, a punch mounted in said head and projectable through the work to form a hole therein, the said pilot while in projected position extending through the work to align the work with the rivet, and a rivet set also mounted in said head for driving the rivet through the hole in the work and against the anvil and retracted pilot to upset the rivet, the said rivet while being driven through the hole in the work engaging the pilot to be guided thereby and to eject the same from the work and to return the pilot to retracted position, shiftable means operatively connected to the said shiftable head and coordinated therewith for projecting the pilot beyond the mouth of the opening in the anvil after the punching operation and for holding the end of the pilot substantially flush with the mouth of the opening in the anvil during the rivet upsetting operation, and a second means operatively connected to the shiftable head and coordinated therewith for removing the aforementioned shiftable means from beneath the pilot to permit the pilot to retreat into the anvil during the punching operation.

3. A punching and riveting machine comprising an anvil over which the work is placed, a shiftable head shiftable to alternately position the punch and rivet set over said anvil, a punch mounted in said head for punching a hole through the work, a pilot guided in said anvil and projectable through the opening in the work for maintaining the work in position on the anvil and retractable to a position flush with the face of the anvil whereby the pilot serves as a part 35 of the anvil in upsetting the rivet, and a rivet set also mounted in said head for driving a rivet through the hole in the work and against the anvil to upset the same, the rivet upon being driven through the hole in the work ejecting the pilot from the hole in the work, shiftable means operatively connected to the said shiftable head and coordinated therewith for projecting the pilot beyond the mouth of the opening in the anvil after the punching operation and for holding the end of the pilot substantially flush with the mouth of the opening in the anvil during the rivet upsetting operation, and a second means operatively connected to the shiftable head and coordinated therewith for removing the aforementioned shiftable means from beneath the pilot to permit the pilot to retreat into the anvil during the punching operation.

4. A punching and riveting machine comprising an anvil having an opening over which the work is placed, a shiftable head shiftable to alternately position the punch and rivet set over said anvil, a punch mounted in said head for punching a hole in the work, a pilot reciprocably mounted in said opening projectable beyond the mouth of the opening through the hole in the work to maintain the work in position on said anvil, and a rivet set also mounted in said head for driving a rivet through the hole in the work and against the anvil to upset the same, the rivet 60 while being driven by the rivet set engaging the end of the pilot to be guided thereby through the opening in the work and to eject the pilot from the hole in the work, a shiftable seat and cam member positioned beneath the pilot and oper- 70

atively connected and coordinated with said shiftable head whereby the said shiftable member is shifted after the punching operation to cam the pilot through the hole in the work for maintaining the work in position on the anvil and is thereafter shifted to position the seat portion beneath the pilot to hold the upper end of the pilot flush with the mouth of the anvil to serve as a part of the anvil in upsetting the rivet, and a second means operatively connected and coordinated with the shiftable head for shifting the cam and seat member from beneath the pilot to permit the pilot to retreat into the anvil during the punching operation.

15 5. A punching and riveting machine comprising an anvil having an opening therein, a pilot movably mounted in the opening in said anvil, a shiftable head shiftable to alternately position the punch and rivet set over said anvil, a punch 20 mounted in said head and projectable through

the work to form a hole therein, a rivet set also mounted in said head for driving a rivet through the hole in the work and to retract the pilot, a shiftable seat and cam member positioned beneath the pilot and operatively connected and coordinated with said shiftable head whereby the said shiftable member is shifted after the punching operation to cam the pilot through the hole in the work for maintaining the work in position on the anvil and is thereafter shifted to position the seat portion beneath the pilot to hold the upper end of the pilot flush with the mouth of the anvil to serve as a part of the anvil in upsetting the rivet, and a second means operatively connected and coordinated with the shiftable head for shifting the cam and seat member from beneath the pilot to permit the pilot to retreat into the anvil during the punching operation.

WILLIAM E. MARCHANT. 20
